BAR LIQUOR DISPENSER

George W. Bayers, Jr., 2314 Champa St., Denver, Colo.

Filed June 14, 1962, Ser. No. 70,546

Term of patent 14 years

(Cl. D2—3)

FIG. 1.

FIG. 2.

FIG. 4.

FIG. 3.

FIGURE 3 is a view of one end thereof with the other end and back being flat and plain;

I claim:

The ornamental design for a bar liquor dispenser, as shown and described.
